UNITED STATES PATENT OFFICE.

CHARLES A. NEEDHAM, OF NEW YORK, N. Y., ASSIGNOR TO HIMSELF AND
ELIAS P. NEEDHAM, OF SAME PLACE.

THEATER-STAGE.

SPECIFICATION forming part of Letters Patent No. 258,539, dated May 23, 1882.

Application filed February 24, 1882. (No model.)

To all whom it may concern:

Be it known that I, CHARLES A. NEEDHAM, of the city and county of New York, in the State of New York, have invented a certain 5 new and useful Improvement in Theater-Stages, of which the following is a specification.

My invention consists in the combination, with the proscenium of a theater, of a multiple stage provided with a vertical axis and arranged opposite the center of the proscenium, and adapted to be turned or rotated to bring different portions adjacent to the proscenium. This multiple stage comprises a number of 10 separate stages, formed by partitions extending radially to the axis of the multiple stage. By this construction I obviate the necessity of carrying stage furniture or accessories up and down stairs, as is necessary where a vertically-moving system of stages is used, and I also ob- 15 viate the necessity of making a deep pit below the stage, as has to be done with such vertically-moving system.

In the accompanying drawing I have represented a plan of a theater provided with my 20 improved multiple stage.

A designates the auditorium of a theater. B designates the proscenium, and C designates the stage-boxes thereof. D designates the stationary stage portion on which the foot- 25 lights are ordinarily arranged.

In carrying out my invention I employ a system of stages or a multiple stage which forms one structure and comprises two or more stages, E, four being here represented. This 30 system of stages is arranged opposite the center of the proscenium, and is adapted to rotate or turn upon a vertical axis, so as to bring any of the stages E opposite or adjacent to

the proscenium, and economizes space, as the front of the floor D is commonly rounded or 40 curved, and this system may conform thereto, as represented. The several stages are separated by radial vertical partitions, and taper in a horizontal plane toward the center of the system or multiple stage; but this is rather an 45 advantage than otherwise, as scenes are always set flaring toward the auditorium, to give them the proper perspective. The several stages are in the same horizontal plane, and are moved horizontally to bring them into and 50 out of position, and, as they are parallel with the front portion, D, very little labor is required in setting the acts, and furniture, scenes, and other stage accessories do not have to be carried up and down, as in setting the acts in 55 a vertically-movable system of stages.

What I claim as my invention, and desire to secure by Letters Patent, is—

1. The combination, with the proscenium of a theater, of a multiple stage provided with 60 a vertical axis and arranged opposite the center of the proscenium, and adapted to be turned or rotated to bring different portions adjacent to the proscenium, substantially as described.

2. The combination, with the proscenium of 65 a theater, of a multiple stage provided with a vertical axis and with radial vertical partitions arranged opposite the center of the proscenium, and adapted to be turned or rotated to bring different portions adjacent to the pro- 70 scenium, substantially as described.

CHAS. A. NEEDHAM.
